UNITED STATES PATENT OFFICE.

WILLIAM DAVES, OF CRANSTONS, NEW YORK.

ELECTRIC RAILWAY-SIGNAL.

SPECIFICATION forming part of Letters Patent No. 349,927, dated September 28, 1886.

Application filed November 6, 1885. Serial No. 182,054. (No model.)

To all whom it may concern:

Be it known that I, WILLIAM DAVES, a citizen of the United States, residing in Cranstons, in the county of Orange and State of New York, 5 have invented certain new and useful Improvements in Electric Railway-Signals, of which the following is a specification.

My invention relates to the class of devices employed for controlling the connections of 10 electric circuits for signaling at railway-crossings the approach of trains.

The object of the invention is to provide means for causing an alarm to sound or a signal to be given in the neighborhood of a crossing 15 when trains are approaching in either direction on a single track, while it remains unaffected by trains receding from the crossing.

The invention consists in constructing an interlocking device for closing a circuit through 20 an alarm or signaling device in such manner that two electro-magnets must be vitalized to complete the circuit. A given one of these electro-magnets must be vitalized before the 25 other in each instance, in order that the device shall respond. If the second is first vitalized, it locks the first magnet so that its armature cannot be actuated, and at the same time the armature of the first holds the other armature in such position as to prevent it from completing the connections of the alarm-circuit.

In the accompanying drawing, there is illustrated an organization of circuits and apparatus embodying the features of the invention.

Referring to the drawing, A represents a 35 single-track railway, and it is supposed that a crossing is at or near the point B.

C represents a signaling device, in this instance a vibrating bell included in the circuit of a local battery, o. The connections of this 40 battery are designed to be completed by the contact of a spring, c', with an arm, c'', under the influence of the pressure exerted by an armature-lever, d, of an electro-magnet, D. Upon this armature-lever there is a catch, d', 45 which is designed to pass behind a corresponding catch, e', upon an armature, e, applied to an electro-magnet, E. If the electro-magnet D be vitalized while the armature e is away from its magnet, the catch d' will be engaged 50 by the catch e', and thus the armature d will

be prevented from coming toward its electro-magnet and closing the circuit of the battery o. If, however, the electro-magnet E be first vitalized, and then the electro-magnet D, then both armature-levers will be allowed to come 55 forward and the circuit of the battery will be completed. The positions of the armatures are so adjusted that while the armature e can pass toward its electro-magnet, provided the armature d be in its backward position, yet 60 if the latter be drawn slightly forward then the detent or catch d' will pass behind the hooked end of the catch e' and prevent the latter from coming forward when the electro-magnet E is vitalized, thus insuring that the 65 armature d cannot close the circuit of the local battery in any event when the electro-magnet D is vitalized first. The means whereby these electro-magnets are vitalized in the proper succession are as follows: At each of two 70 suitable points, F' and F'', at the required distances from the crossing B, are placed two circuit-closers, as shown at f'f'' and f''f''. These circuit-closers may be of any convenient form adapted to complete the connections between 75 the rails a of the track and the conductors 1, 2, 3, and 4, respectively, by the operation of a passing train. The conductor 1 leads from the circuit-closer f' to a conductor, 5, including the coils of the electro-magnet E and connected with one pole—say the positive—of a 80 battery, O'. The negative pole of this battery is connected by a conductor, 6, with the rails a. When therefore the circuit is completed between the rail and the conductor 1 by a 85 train passing the circuit-closer f', the electro-magnet E will be vitalized and its armature-lever drawn forward. The train proceeding upon the track in the direction indicated by the arrow x then closes the circuit between the 90 rail and the conductor 2 by means of the circuit-closer f''. The conductor 2 is connected with a conductor, 7, leading through the coils of the electro-magnet D to one pole—say the negative—of a battery, O''. The remaining 95 pole of this battery is connected by the conductor 6 with the rails a. The electro-magnet D will therefore be vitalized, and the armature e, having been drawn out of its path, the armature d will be drawn forward, thus closing 100

the circuit of the battery o and causing the bell to be actuated. The train passing toward the crossing passes from the circuit-closer f' and allows the circuit through the electro-magnet 5 E to be broken and its armature-lever to fall back before the electro-magnet D is demagnetized. The armature d falls behind the armature e , thus locking it forward and causing the circuit to remain closed even after the train 10 has passed the circuit-closer f^2 . When the train has reached the crossing, it is necessary that the signal should be released and the circuit of the battery o interrupted. For this reason a circuit-closer, f^5 , is employed, and 15 this is connected by a conductor, 8, with the conductor 5, leading through the electro-magnet E . The train reaching the crossing closes the circuit through this device, thereby causing the electro-magnet E to be vitalized and 20 its armature-lever drawn forward, thus releasing the armature d , which immediately falls away from its magnet, thus opening the circuit of the battery o . The train continuing reaches the circuit-closer f^4 and completes the 25 circuit through the magnet D by way of the conductor 4, leading from the circuit closer to the conductor 7; but the armature d is prevented from coming forward and closing the circuit of the local battery o by reason of the 30 hooked catch e' upon the armature e . The circuit is then closed through the magnet E by the circuit-closer f^3 , which is connected by the conductor 3 with the conductor 5. The armature e , however, is prevented from coming forward by reason of the hooked extension e' being engaged by the catch d' upon the lever d , it being understood that the armature d is held 35 forward by its electro-magnet D . The circuit of the battery o , therefore, will not be completed by the train passing from the crossing over the circuit-closers f^3 and f^4 . It is evident that a train passing in the direction opposite that indicated by the arrow q will first arrive at the circuit-closer f^3 and complete the 40 circuit through the electro-magnet E . Then by reason of the circuit-closer f^4 the electro-magnet D will be vitalized, and thus operate the signaling devices in precisely the same manner as described with reference to a train passing 45 in the direction of the arrow and operating the circuit-closers f' and f^2 . The signal will then remain actuated until the train arrives at the crossing B , whereupon it is released in the manner described. The train subsequently 50 passes the circuit-closers f^2 and f' in succession without operating the signal.

I claim as my invention—

1. The combination, substantially as hereinbefore set forth, with a railway-track, of two electro-magnets, a circuit-closing device, means for completing a circuit through one of these magnets by a train moving in a given direction, and then completing a circuit through the second, and thereby operating the circuit-closer, means for demagnetizing the first magnet, and thereby locking the circuit-closer, and means for subsequently vitalizing the first-named magnet, and thereby releasing the circuit-closer, substantially as described. 60

2. The combination, substantially as hereinbefore set forth, with a railway-track and four circuit-closers located along said track, of an electro-magnet, means for vitalizing said electro-magnet by the operation of either of the two extreme circuit-closers, a second electro- 70 magnet, means for vitalizing the same by the operation of either of the remaining circuit-closers, a signaling device controlled by said electro-magnets and operated only when the first of said electro-magnets is first vitalized, 75 and then the second, substantially as described. 80

3. The combination, substantially as hereinbefore set forth, of a railway-track, two circuit-closers operated by a train passing along said track, two electro-magnets respectively 85 included in the circuits controlled by said circuit-closers, means for vitalizing said electro-magnets in the succession in which the corresponding circuit-closers are operated, a signaling device, a local circuit for the same, and means for closing said circuit only when said circuit-closers are operated in a given succession. 90

4. The combination, substantially as hereinbefore set forth, of a railway-track, two circuit-closers operated by a train passing along said track, two electro-magnets respectively included in the circuits controlled by said circuit-closers, a signaling device, a local circuit for the same, means for closing said circuit 95 100 only when said circuit-closers are operated in a given succession, and a third circuit-closing device for subsequently completing the circuit completed by the first of said circuit-closers.

In testimony whereof I have hereunto subscribed my name this 28th day of October, A. D. 1885. 105
